(57) **CLAIM**

An ornamental design for a stock body for a rifle, as shown and described.

DESCRIPTION

FIG. 1 is a right perspective view of the stock body for a rifle.

FIG. 2 is a top plan view of the stock body for a rifle.

FIG. 3 is a rear plan view of the stock body for a rifle.

FIG. 4 is a right plan view of the stock body for a rifle.

FIG. 5 is a left perspective view of the stock body for a rifle.

FIG. 6 is a bottom plan view of the stock body for a rifle.

FIG. 7 is a front plan view of the stock body for a rifle; and,

FIG. 8 is a left plan view of the stock body for a rifle.

The broken lines shown of interior structure in FIG. 7 and of indicia in FIGS. 1, 4 and 8 is included for the purpose of illustrating environment and forms no part of the claimed design.
